UNITED STATES PATENT OFFICE

NICHOLAS H. STUART, OF BUFFALO, NEW YORK, ASSIGNOR TO REMINGTON RAND INC.,
OF BUFFALO, NEW YORK

BOOKBINDER

Application filed February 8, 1930. Serial No. 426,935.

This invention relates to book binders and it has particular reference to a binder adapted to hold a plurality of sheets or leaves within a cover in a detachable manner.

More specifically, the invention contemplates the provision of a binder having a cover within which are disposed a number of hinge members or pins having fastening devices pivotally mounted thereon for detachable interlocking engagement with other elements adapted to hold the leaves together. In the specific embodiment of the invention hereinafter described and illustrated, the fastening device is formed with a plate and slide which, by proper manipulation, either reveal or close an aperture of such size as to permit of the passage therethrough of a stud head. The stud head is formed on a plate or strip provided with prongs for impaling a number of sheets of paper. When the aperture in the fastener is revealed, the fastener may be dislodged from or engaged with the stud head, to permit of the addition or removal of sheets, and when the aperture is closed around the stud head, the leaves are firmly bound within the cover. Associated with the fastening assembly and forming a part thereof are one or more spacers which are employed to obtain the correct spacing of the pivoted fasteners relative the thickness of the binder and included leaves, and also to reinforce the book cover and to maintain the parts in proper relation.

The invention provides a book binder of the removable leaf type which is simple in construction, which retains the sheets firmly in place, and which permits of the removal or insertion of a leaf on either front or back of a stack of assembled leaves.

The various objects and advantages of the invention may be understood from the following description of a specific embodiment of the principles thereof, illustrated in the accompanying drawings, wherein,

Fig. 1 is a fragmentary plan view of an open binder with the fastening means disengaged from the leaves.

Fig. 2 is a fragmentary plan view of an open book binder with the fastening means

engaging means for holding the leaves together.

Fig. 3 is a cross-sectional view taken on the line 3—3 of Fig. 1, showing the construction of the leaf-impaling means.

Fig. 4 is a cross-sectional view of a closed book binder taken on the line 4—4 of Fig. 1.

Fig. 5 is a cross-sectional view of a spacing strip taken on the line 5—5 of Fig. 1.

Fig. 6 is a perspective view of the several elements entering into the fastening unit.

Fig. 7 is a perspective view of the several elements entering into the spacing unit adapted to be associated with the fastening elements.

Fig. 8 is a fragmentary perspective view of an assembled book binder with the fastening device detached from the leaf-impaling device.

The binder comprises a book cover 10 having a front portion 11, a rear portion 12, and an intermediate back web 13 to which the portions 11 and 12 are hingedly connected. The cover unit may be similar in construction to any type of book cover. The portions 11 and 12 may be stiff or flexible but the portion 13 should be flexible as is the case with all types of binders.

On the inside faces of the portions 11 and 12 adjacent the junctions of these portions with the back 13, are a plurality of hinge members 14 which are riveted or otherwise secured to the covers as indicated by the numeral 15. Any number of these hinges may be employed depending upon the size of the book. In the drawings four hinge members are shown and this will usually suffice for ordinary purposes. Each hinge member 14 is formed of sheet-metal or similar material and is provided with spaced pin

bearings 16 adjacent its edge, which is adapted to be disposed adjacent the junction of the front or back cover and the back 13 of the cover 10. The bearings 16 may be formed by rolling the edge of the sheet material into cylindrical form. The bearings 16 are spaced and the metal is cut away between them, as indicated by the reference numeral 17, to provide a pocket in which other elements of the assembly may be folded when the book

is closed. It is desirable to position pairs of hinge members 14 in aligned relation on the covers 11 and 12.

A plurality of pins 18, provided with bent ends 19 to facilitate their insertion or removal, pass through the pin bearings 16. Mounted upon the intermediate portion 21 of the pin 18 is a fastening device indicated generally by the reference numeral 22 and shown in detail in Fig. 6. This fastening device consists of a plate member 23 provided along one edge with a cylindrically turned portion 24 forming a bearing adapted to surround the pin 18. A portion of the same edge is not curled however, but forms a straight projecting finger 25 which limits the rotation of the plate 23 on the pin 18. This limitation of rotation facilitates manipulation of the fastener as a unit. The opposite edge of the plate 23 is bent at right-angles to form a flange 26 which serves as a guide and retaining means for a slide member 27. On the face of the plate 23 is a headed stud 28 adapted to pass through a slot 29 formed on the slide 27. Below the stud 28 in the plate 23 is a circular aperture 31.

The slot 29 formed in the slide 27 is elongated and it terminates at one end in an enlarged circular portion 32 of substantially the same diameter as the aperture 31 in the plate 23. The slide is also formed with angularly offset ends 33 and 34. The two elements, (the plate 23 and the slide 27), are interlocked for sliding movement by positioning the slide 27, formed in the manner shown, over the plate 23, and subsequently passing the stud 28 through the plate and the slot 29. Or, one end of the slide 27 may be straightened out and the portion 32 of the slot 29 positioned over the stud 28 so that the slide 27 may be moved along the plate 23 with the head of the stud 28 engaging the surface of the slide 27 adjacent the narrow portion of the slot 29. Then the straight end of the slide 27 may be bent into the position illustrated. When assembled, it will be apparent that movement of the slide 27 over the plate 23 in one direction permits of the registry of the apertures 31 and 32, while movement in the opposite direction reduces the effective area of the aperture 31 by positioning the narrow portion of the slot 29 over segments of the cylindrical hole 31.

This "key hole lock" type of fastener is pivotally mounted on the pin 18 between the pin bearings 16. It is adapted to be swung toward or away from a pile of sheets 35 which may be assembled in the binder.

As illustrated best in Fig. 3, the pile of book leaves 35 are provided with a plurality of aligned marginal perforations 36, which permit of the passage of leaf-impaling means collectively securing the sheets together. The impaling means herein delineated consists of a pair of elongated flat metal plates 37, each

of which is provided with alternating long hollow leaf-impaling bars 38 and short complementary studs 39. If desired, the bars 38 may be made in two sections that may be screwed together in order to permit of the linear adjustment of the bars. The outer section of each bar 38 is formed with a longitudinally extending aperture adapted to receive the pin 39 formed on the opposite plate 37. It may be observed that with this construction, either plate 37 may be removed from the stack of leaves 35 together with a number of leaves, so as to give ready access to a sheet adjacent either face of the stack without destroying the alignment of the apertures 36.

Disposed on the outer surfaces of the plates 37, and to be aligned with the apertures 31 in the plates 23, are studs 41 formed with a recessed neck 42 and an enlarged head 43. When the fastener 22 is brought over the stud 41 with the slide 27 so moved as to reveal the maximum effective area of the aperture 31, the head 43 of the stud 41 may be pushed through the now aligned apertures 31 and 32, thereby effecting the engagement of the plate 37 and the fastener 22. By means of this immediate connection, the stack of leaves 35 may be firmly bound between the covers 11 and 12 by sliding member 27 in the opposite direction, so that the narrow portion of the aperture 29 engages the under side of the head 43.

This construction permits of the ready introduction or removal of a sheet from the stack 35 and the change may be made by operating the fasteners 22 secured to either front or rear cover of the book. The leaves are firmly bound in position when the fasteners are locked, and hence the assembled volume possesses the desirable features of a permanently bound book while retaining the feature of interchangeability of leaves sought for in loose leaf binders.

While the binder as thus far described is, in and of itself operative and highly useful, nevertheless it is susceptible of improvement by the inclusion of a spacing strip which serves to strengthen the binder and to effect a great range of adaptation of the book cover to stacks of leaves of varying thicknesses. This spacing strip is referred to in the several assembled features by the numeral 45 and it is illustrated in detail in Figs. 5 and 7.

The spacing strip is positioned between opposed pins 18, the recess 17 of the hinge member 14 being so dimensioned as to accommodate pin bearings formed on the strip 45 on the mid portions 21 of the pins 18. Each strip 45 is made in two parts, and advantageously is formed of thin and resilient sheet-metal. One portion, 46, is formed along one edge with spaced pin bearings 47 and is also formed with a plurality of centrally disposed regularly spaced holes 48. The other

portion, 49, is likewise formed with pin bearings 51 but is provided with only one hole 52 in line with the holes 48 in the portion 46. The top and bottom edges of the portion 49 have offset ears as indicated by the numeral 5 53 to overlie the straight edges of the portion 46, and these offset edges are formed with slots 54 which extend below the surface of the portion 46.

Extending through the slots 54 and under 10 the lower surface of the portion 46 is a bow spring 55 of thin sheet-metal, having curled ends 56 to prevent its removal from the slots. The bow 55 is provided at its mid-portion with a pin 57 that normally passes through 15 a registering hole 48 in the member 46 and the hole 52 in the portion 49, thereby locking the portions 46 and 49 together. When the curled ends 56 are squeezed between the fingers, however, the bow 55 assumes the position shown in dotted lines in Fig. 5, when the pin 57 clears the holes 48 and 52, and so permits of longitudinal movement of the parts 46 and 49 to another and more desired 20 position.

In assembly, the portions 46 and 49 are positioned between oppositely disposed hinge members, the pin 18 holding a spacing strip section and a fastening unit 22 to each member 14. Depending upon the thickness of the 30 stack of leaves 35, the length of the strip 45 is varied so that, when the book is closed, as indicated in Fig. 4, the strip 45 is of proper length to relieve heavy strains from the flexible back web 13. In closing the fasteners 35 on the stack preparatory to locking, it will be found that proper adjustment of the strips 45 facilitates operation, the fasteners 22 swinging into the desired position by the link 40 action of the strip 45.

From the foregoing description, it will be apparent that I have provided a simple and rugged structure for firmly binding leaves together in more or less permanent relation, 45 and that the principles of the invention permit of wide departures in the various physical embodiments which may be designed. It will be understood, therefore, that I do not desire the invention to be limited to the specific embodiment described, but that I intend to include such other structures as embody 50 the features set forth in the following claims.

What is claimed is:

1. A binder comprising a book cover having 55 front and rear portions and a connecting web portion, hinge members secured within the front and rear portions adjacent the web, pins mounted in the hinge members, fasteners mounted on the pins for rotation with respect to the hinge members, plates provided with impaling means for collectively holding a plurality of leaves, and means on the plates engageable with the fasteners for locking cooperation therewith.

2. A binder comprising a book cover, a hinge pin mounted within the cover adjacent the pivotal edge thereof, a plate provided with impaling means for collectively holding a plurality of leaves and formed with a 70 projecting stud having an enlarged head, and a fastener mounted on the hinge pin and formed with an aperture having an enlarged portion adapted to be aligned with said stud and means on the fastener for engaging the 75 under side of the stud head for interlocking the plate and the fastener.

3. A binder comprising a hinge member provided with a pin bearing, a pin in the bearing, a plate provided with an aperture, and a headed stud, said plate being mounted for rotation on the pin, a slide formed with an elongated slot having an enlarged portion mounted on the plate for longitudinal movement and secured to the plate by means of the interengagement of said stud and elongated slot, and means to limit the movement of said slide over said plate whereby the aperture of the plate and enlarged portion of said slot in the slide may be aligned while maintaining said interengagement of the stud head and elongated slot.

4. A binder comprising a front cover, a rear cover, and a back web interconnecting said covers for hinging movement, pin bearings oppositely mounted within the covers, hinge pins in the bearings, a fastener rotatably mounted on each pin, leaf-holding means provided with portions adapted to interlock with said fasteners, and a spacing strip mounted on the pins to effect a predetermined spacing of opposite fasteners and the covers by which they are carried.
